UNITED STATES PATENT OFFICE

ORLANDO SCOTTI, OF VIENNE, FRANCE

CONTINUOUS HAT BEATING MACHINE

Application filed March 31, 1930, Serial No. 440,583, and in France January 31, 1930.

This invention relates to improvements in hat beating machines in which the supports for the hoods are moved automatically in an endless circuit and receive a rotatory movement about their axes during the period of beating the speed of which rotation is proportional to the speed of their linear displacement. In these machines, the hood supports are mounted on shafts rotatably mounted on bearings secured to the links of an endless belt or chain.

The essential features of the invention are as follows:

1. The hood supports travel horizontally that is remain in a substantially vertical position, during the beating of the thongs arranged side by side on either side of the upper portion of the endless chain.

2. The bearings for the hood spindles are connected in a removable manner on metal supports of suitable shape secured to the links of the endless chain.

3. This chain passes at each end over two sprocket wheels and carries a double row of grooved rollers, one row ensuring a smooth passage over the teeth of said sprocket wheels, whilst the other serves to support and guide the chain in the two straight parts of the chain's path.

4. The whole apparatus is mounted inside a frame provided at its two ends with openings for the passage of the hood supports.

5. The beating thongs, are not all of the same length in order that their action may be uniform over the whole surface of the hood, and they may be adjusted in position by displacement of their axes in suitable grooves to beat the hoods in a suitable and efficient manner, whatever their shape, their degree of conicity and their height. They may also be individually adjusted on their supports to compensate for the troublesome effect occurring due to their shortening after use.

45 The invention will now be described with reference to the accompanying drawings.

Fig. 1 is a longitudinal section on line 1—1 of Fig. 2.

50 Fig. 2 is a transverse section on line 2—2 of Fig. 1.

Fig. 3 is a transverse section made at larger scale of the hood supports and the links forming the chain.

Fig. 4 is a plan of a part of the chain.

Fig. 5 shows a detail of the mounting of the thongs.

Fig. 6 is a diagrammatic view of the suction arrangement for a number of machines.

According to the present invention, the bearings 1, shafts 2, hood supports 3 are mounted in a removable manner by bolts 4 on metal corners 6 secured on the interior links 5 of the endless chain. These links are pivoted to the exterior links 5 of the chain by pins 8.

This chain is driven by two sprocket wheels 9 arranged at each end of the machine. Grooved rollers 11 ensure easy running of the chain over the teeth of the aforesaid wheels 9, whilst other rollers 13 travelling on runways 15 and 16 support and guide the chain both in the upper part of the circuit during beating and in the lower part during the return. This latter arrangement allows for avoiding a too rapid lengthening of the chain.

The links and rollers 11 are provided with hubs 17 (Fig. 3) permitting to reduce oiling to a minimum so as to eliminate the risk of spots of oil getting on to the hats.

The shafts 2 for the hood supports 3 each carry a pinion 18 which during the straight portion of the upper circuit during beating engage with a rack 20.

The apparatus is mounted in a casing 21 provided with an openings 22 and 23 at either end for the passage of the hood supports.

It is through these openings that at one end the hats are fed and placed on the supports and at that, at the other end, they are removed after beating.

The arrangement of affixing the supports 1 to the links 5 of the chain by means of the bolts 4 and the corners 6 allows for easily and rapidly removing these latter or reassembling them without taking down the machine. Repairs to a pin or a support or the replacement of unsuitable straps may also be effected without stopping the machine for very long. Further the shafts 24 and 25 on which are mounted the spiders 26 and rods 27 for the beating

thongs can be adjusted in position in grooves 30 and 31, provided in the casing 21, to change their position to beat the hat conveniently and efficiently whatever its shape may be 5 which varies with its degree of conicity and its height.

Moreover the clamps 32 allow for individual loosening of the rods 27 on which the lashes or thongs 33 are mounted and of re-clamping them after having moved them the required distance nearer to the hood supports to compensate for wear. These thongs are not all of the same length as is shown in Fig. 5 so that all parts of the hoods will be beaten in a uniform manner as it will be seen that for the shape of hood shown the long thongs will reach to the top of the head piece where they will work efficiently but will only operate on the sides of the hood in a less efficient manner. On the other hand the neighbouring thongs which are shorter beat the sides and operate in these latter in a very efficient manner.

The profile of the beating thongs as shown in Fig. 5 may be made up of a number of separate strips, more or less, according to the degree of beating to which the hood is to be subjected and the process of dyeing employed (alizarine colours, acids, chrome or mineral colours).

The number of strips should be proportional to the weight of the hat.

Lastly a suitable system of suction 35 appropriate for each machine allows for clearing the frame 21 of dust raised by the thongs.

In factories using a number of machines the diagrammatic arrangement shown in Fig. 7 may be employed in which the suction pipes of each machine are connected to a single fan 40.

As will be understood and as results from what has been described the invention is not limited to the single means of operation above described nor to its different parts but includes on the contrary all variations containing the application of the above arrangement and notably that in which the chain formed of articulated elements 5 is replaced by one or more grooved flexible blades (cables, belts, 50 steel bands) on which the hood supports are mounted.

Having now particularly described and ascertained the nature of my said invention and in what manner the same is to be performed, 55 I declare that what I claim is:

Continuous hat beating machine, comprising two sprocket wheels, a movable endless chain carried by said sprocket wheels, rotary hat-blocks each pivoted on a bracket secured to a separate link of said endless chain so as to remain in a substantially vertical position during the beating of the hats, a pinion carried by each of said blocks, a rack fixed to the frame of the machine so as to mesh with those 65 of said pinions travelling along the upper

straight portion of said endless chain, two horizontal parallel shafts, rotary whips carried by said shafts and working in the path of said blocks along said upper straight portion of the endless chain, means for driving simultaneously one of said sprocket wheels and said two shafts, and means permitting the adjustment of the position of each beating whip individually with respect to the blocks, said means comprising a rotary spider constituting the support of each of said whips, grooves provided in the radial arms of said spiders and clamps to which are fixed the lashes of said whip, said clamps being slideable in said grooves and fixable in any desired position along said grooves in order to adjust the useful length of said lashes.

Signed at Lyon, Rhone, The French Republic, this 28th day of February, A. D. 1930.
